Primary Examiner — Deanna L Fluegeman(74) *Attorney, Agent, or Firm* — Banner & Witcoff, Ltd.(57) **CLAIM**

The ornamental design for a display screen with graphical user interface, as shown and described.

DESCRIPTION

The FIGURE is a front view of a display screen with graphical user interface showing my new design.

The broken line showing of the display screen is included for the purpose of illustrating the environment of the claimed design and forms no part thereof. The broken line showings of a portion of the runner and other aspects of the graphical user interface illustrate portions of the graphical user interface that form no part of the claimed design.
